UNITED STATES PATENT OFFICE.

JOHN P. NORMANN, OF CROOKSTON, MINNESOTA.

BOOKBINDING-MACHINE ATTACHMENT.

1,351,060.

Specification of Letters Patent. Patented Aug. 31, 1920.

Application filed April 2, 1917. Serial No. 159,192.

To all whom it may concern:

Be it known that I, JOHN P. NORMANN, a citizen of the United States, and resident of Crookston, in the county of Polk and State 5 of Minnesota, have invented certain new and useful Improvements in Bookbinding-Machine Attachments, of which the following is a specification.

This invention relates to bookbinding and 10 has more especial reference to a novel attachment for wire stapling machines.

The dominant object of the invention is to provide a guide attachment for wire stapling machines, whereby a foldable book having either stub or duplicate leaves provided 15 with tearing lines to facilitate separation thereof can be so arranged when folded as to have each of the leaves through the book fold on the tearing line, thus, rendering the 20 book flat and compact.

It is also an object of the invention to provide a guide which is capable of adjustment in order that foldable books varying in size may be bound thereby.

25 Among other aims and objects of the invention may be recited, the provision of an attachment of the character mentioned with a view to compactness, and in which the number of parts are few, the construction 30 simple, the cost of production small, and efficiency of operation high.

The improvements in the details and arrangement of parts will be apparent from 35 an inspection of the accompanying drawings, in connection with the specific description hereinafter contained, and wherein the preferred embodiment of the invention is disclosed for the purpose of imparting a full understanding of the same.

40 In the drawings:

Figure 1 is a fragmentary side elevation of a wire stapling machine with my improved attachment applied thereto; and

Fig. 2 is a perspective of the novel attachment.

45 Referring now more specifically to the drawings, wherein like reference characters designate corresponding parts in the several views, I have shown by way of illustration, the improved guide attachment as applied to the work bed of a conventional type of 50 stapling machine designated S.

The attachment comprises a substantially 55 rectangular plate 1 having a straight forward edge, which edge is sharpened or tapered sufficiently to cause the acute bending

or folding of the book at a line on the tearing line and constitutes a guide which can be adjusted according to the position of the tearing lines upon the book leaves, that is, 60 whether the same are arranged in proximity of the point at which the various leaves of the book are bound or are arranged at a greater distance therefrom. A rectangular opening 2 is formed within the plate 1, and 65 obviously, serves as means for permitting the stapling apparatus of the machine to pass therethrough in order that the binding wires may be securely clenched upon the reverse side of the book. Elongated slots 70 3 are also formed in the plate and are disposed longitudinally of the opening 2, whereby set screws 4 may be passed therethrough and turned into engagement with suitable screw threaded recesses formed in 75 the work receiving bed of the stapling machine S. By loosening the set screws 4, the plate may be moved longitudinally of the work bed in order that the sharpened straight edge of the same may be adjusted 80 with relation to the forward edge of the said work bed. By this means, foldable books varying in size may be properly positioned upon the guide plate in order that the heads of the same will be so positioned 85 with relation to the stapling apparatus of the machine as to be efficiently clenched or bound thereby.

From the foregoing, it will be apparent 90 to workers in the art, that with my improved guide attachment, foldable books may be bound in such a manner as to permit the same to be foldable flat and smoothly when finished; the book during the operation is folded over the forward edge of the 95 guide plate 1, thereby, so positioning the perforations or tearing lines of the various pages of the same as to accord with the shape assumed thereby when in its folded position.

100 It is of course to be understood, that the invention is not limited to use upon wire stapling machines, but may be equally as well adapted for use upon various forms and types of book binding machines, irrespective of the construction of the same.

105 As above indicated, I do not wish to be understood as confining the invention to the particular embodiment chosen for illustration herein, nor to the exact construction, arrangement and adaption of the parts shown and described, but I reserve the right to 110

make any changes and alterations that fairly fall within the spirit and scope of the invention.

I claim:

- 5 The combination with a machine of the class described including a supporting table having a stationary anvil thereon and an arm carrying a stapler, of a plate bearing upon said table and having a beveled edge

extending beyond the outer edge of the 10 same, said plate being provided with an opening positioned constantly beneath the stapler upon the anvil, and means for adjustably supporting the plate upon the table.

In testimony whereof, I affix my signature 15 hereto.

JOHN P. NORMANN.
